UNITED STATES PATENT OFFICE.

VICTOR L. RONCI, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed April 27, 1923. Serial No. 634,978.

This invention relates to electron discharge devices and more especially to high power vacuum tubes and has for its object an improved method of assembling metallic 5 and non-metallic portions of the structure.

In one type of power tube, the cathode is strung over hooks carried by each of two blocks of insulating material. The shank of each hook passes through an aperture in one 10 of the insulating blocks and is held in position thereon by nuts screwed thereon at either side of the insulating block.

According to this invention, each block of insulating material is provided with a 15 plurality of pairs of apertures. The shank of each filament supporting hook passes through one aperture of each pair and is bent back to pass through the other aperture. The short portion of the supporting 20 member is heated and headed over against the face of the block to prevent the withdrawal of the hook. This arrangement prevents the filament supporting hook from becoming loose in the insulating member due 25 to the difference in expansion of the insulating material and the shank of the hook. It eliminates entirely the use of nuts which cannot be sufficiently tightened to insure a permanent lock because of the frailness of 30 the wire used for the hook and results in a considerable saving in the cost of production because of the elimination of all threads and nuts.

Referring now to the drawing, Fig. 1 35 discloses an electron discharge device constructed in accordance with the invention; Fig. 2 discloses the method of joining together the filament supporting member and the insulating member; Fig. 3 discloses the 40 finished product, and Fig. 4 is a sectional view on the line 4-4 of Fig. 3.

Referring now to Fig. 1, the electron discharge device comprises an enclosing vessel composed of a glass portion 10, to which is 45 sealed a metallic cup-shaped portion 11 which comprises the anode of the device. Within the anode and supported from the glass portion in the usual manner is a grid electrode 12 and a cathode 13, the cathode being supported from hooks 14 mounted on 50 a block of insulating material 15. To attach the filament supporting members to the insulating members, one end of each supporting member is first bent to form a short

hook, and both ends are passed through apertures in the insulating block as shown in Fig. 2, the short end projecting slightly beyond the surface of the insulating block. The aperture through which the short end extends is preferably counter-sunk. The 55 electrodes 16 of a welding machine are brought into contact with the bend of the hook and the short projecting end and current passed therethrough until the wire melts to form a button 17 fitting in the counter-sunk portion. The hook is thus effectively 60 prevented from moving in either direction and the connection between the filament supporting hook and the insulating member remains tight despite the difference in expansion between the insulating material and the hook, thereby avoiding the necessity of 65 threading the ends of the hooks and providing nuts therefor. After the connection has been made between the metallic member and the insulating member, the long end is bent 70 to form a hook 18 from which the filament 75 may be supported.

It is, of course, understood that although 80 this invention has been disclosed in connection with a filament support, it is adapted for other uses within the scope of the appended claims.

What is claimed is:

1. In an electron discharge device, a metallic standard, an insulating member having a pair of apertures carried thereby and a supporting member bent to provide two parallel portions, each of said portions lying in one of said apertures, a head on one of 85 said portions engaging said insulating member whereby movement of the supporting member relative to the insulating member is prevented, and an electrode supported 90 by said member.

2. In an electron discharge device, a metallic standard, an insulating member having a pair of apertures carried thereby, a supporting member bent to provide two parallel portions of unequal length, each of said 95 portions lying in one of said apertures, the shorter of said portions being fused to form a button at the end thereof engaging said insulating member for preventing removal of said supporting member from said insulating member, and an electrode carried by 100 said supporting member.

3. In an electron discharge device a me-

tallic standard, an insulating member supported thereby, said insulating member having a pair of apertures therethrough, a metallic member bent to provide two parallel portions of unequal length each of said portions lying in one of said apertures, a head on the shorter portion engaging said member

whereby movement of said member relative to the insulating member is prevented, and an electrode supported by the longer end of 10 said metallic member.

In witness whereof, I hereunto subscribe my name this 25 day of April, A. D. 1923.

VICTOR L. RONCI.
